(57) **CLAIM**

The ornamental design for an electrical interconnect capsule, as is shown and described.

DESCRIPTION

FIG. 1 is a top perspective view of an electrical interconnect capsule,

FIG. 2 is a bottom perspective view of an electrical interconnect capsule,

FIG. 3 is a front elevation view of an electrical interconnect capsule,

FIG. 4 is a rear elevational view of an electrical interconnect capsule,

FIG. 5 is a right elevational view of an electrical interconnect capsule,

FIG. 6 is a left elevation view of an electrical interconnect capsule,

FIG. 7 is a top elevation view of an electrical interconnect capsule,

FIG. 8 is a bottom elevation view of an electrical interconnect capsule,

FIG. 9 is a close up perspective view of a portion of the top side of an electrical interconnect capsule; and,

FIG. 10 is a close up perspective view of a portion of the bottom side of an electrical interconnect capsule.

The dashed lines shown represent the environment and represent unclaimed subject matter and form no part of the claimed design.
